UNITED STATES PATENT OFFICE.

ORVILLE VINCENT DUTRO AND ARTHUR S. BURROUGHS, OF SPOKANE, WASHINGTON.

WINDING MECHANISM FOR PRINTING-PRESSES.

1,353,948.

Specification of Letters Patent. Patented Sept. 28, 1920.

Application filed April 8, 1919. Serial No. 288,546.

To all whom it may concern:

Be it known that we, ORVILLE V. DUTRO and ARTHUR S. BURROUGHS, citizens of the United States, residing at Spokane, in the county of Spokane and State of Washington, have invented certain new and useful Improvements in Winding Mechanisms for Printing-Presses, of which the following is a specification.

10 The subject matter of the present invention relates to an improved winding mechanism, designed especially for use in connection with a web feed printing press in which the web or paper is fed from a roll and the web after being printed, is cut into sheets. The cutting of these sheets involves both a transverse cut and a longitudinal cut, as for instance where a printed sheet is required that is of less width than the 15 original web, the web is slitted or cut longitudinally and then this partly cut sheet is cut transversely to form the rectangular sheet, leaving the remainder of the web as a continuous strip. The device or attachment 20 of the present invention is designed to rewind this remaining web or strip of paper as it passes, with an intermittent motion through the printing press.

25 The invention consists in certain novel combinations and arrangements of parts wherein a "floating" winding roll is rotated to wind the web, and particularly in the combination and arrangement of compensating features to allow for the increasing 30 size of the roll, an equalizing feature to insure accurate winding of the paper on its roll, and facile release mechanism, together with other details as will be hereinafter pointed out.

40 Figure 1 is a side elevation of so much of a web feed printing press as is necessary to illustrate the application thereto of the device.

Fig. 2 is an end view of the machine as 45 seen from the left in Fig. 1.

Fig. 3 is a view, enlarged, of one of the winding cores.

Fig. 4 is a perspective view of one of the wedge sections of the core, and Fig. 5 is a 50 face view of one of these wedges or core sections, showing in dotted lines the relationship of the other or duplex section.

55 In the preferred embodiment of the invention as illustrated in the drawings, the web which is designated at W, in Fig. 1, is shown in its travel by dotted lines at the

rear end of the printing press P, and traveling over the rolls 1, 2, to a pair of roll supporting rolls 3 and 4, that have their shafts 5 and 6 journaled in the side plates of the 60 attachment P. These two rolls, the one designated as 3 an idle roll and the roll 4 a positively driven roll, are spaced from each other and parallel with each other so that they may support between them and above 65 them the winding roll 7 upon which the web is re-wound from the printing press. The winding roll rests or floats on the top of the supporting rolls and the driven roll 4, by frictional contact with the face of the re-winding roll 7, draws the strip of paper or 70 web over the rolls 1 and 1^A and by the revolving movement imparted to the roll the strip is wound thereon, the roll 4 being positively driven in unison with the draw roll 75 of the feeder and controlled by the same adjustment.

In Figs. 3, 4, 5, the details of construction of the core for the winding roll are illustrated. The core is made up of two wedge shaped sections 8 and 9 each having an end collar 10 recessed at 11 to receive the end 80 of the complementary section so that these ends may be slipped into the recesses to hold the core in normal operative position as in 85 Fig. 3. After the paper roll has been wound upon the core, the core may be withdrawn from the roll with facility by disconnecting one wedge section from the other.

To compensate for the increasing diameter of the winding roll as the winding process progresses, the winding roll is supported by the trunnions 12 on the ends of the core, in the hooks 13 of the compensating side bars 14 that are supported to move vertically in the bearings 15 on the outside of the printing press frame. These compensating bars extend to near the lower portion of the press and are connected by a lower transverse brace 16 upon which the several 90 weights 17 may be deposited as desired. Preferably the brace 16 is formed as a shelf with a pair of spaced vertical pins projecting above its top, and the weights may have openings passing therethrough to slip over 95 the guide pins of the shelf for retention on the shelf. The formation of the hooks 13 which provide bearings for the trunnions 12, prevents displacement of the trunnions, and it will be readily apparent that the weights 100 hold the winding roll down in close frictional contact with its supporting rolls 3

and 4 so that the driven roll 4 may positively turn the winding roll. The weights may be adjusted to provide the proper friction between the winding roll and the supporting rolls to wind the strip on the core, but of course they permit the elevating of the compensating device, as a whole, as the diameter of the winding roll increases, the side bars 14 being lifted in their bearings 15, 15, and 10 the compensating device with its weights is thus lifted as the roll of paper increases in diameter, but at all times the paper roll is held down in frictional contact with the supporting rolls so that the driven rolls 15 may draw the web or paper strip and cause it to be wound on its core.

Accuracy in re-winding and prevention of "drifting" of the paper as it winds on the core is accomplished by the equalizer which 20 consists of a transverse shaft 19 passing through and journaled in the frame of the re-winder and this equalizing shaft has at each end a rack wheel 20, outside the frame, and engaging the rack teeth 21 on the two 25 side bars or compensating bars 14. Thus through the two rack wheels and the two sets of rack teeth the two compensating bars are caused to move in unison and consequently the core of the rewinding roll is held 30 in its adjusted horizontal position to provide for an even and uniform winding of the paper on the roll.

After the strip of web has been wound upon the core, and it is desired to remove the 35 wound roll, the compensating device is lifted bodily by means of the release lever 22, pivotally supported through the link 23, on the bracket 24, and the short arm 25 of this lever is pivotally connected to the shelf or brace 40 16 of the compensating device. Thus the hooks at the upper ends of the side arms are disengaged from their trunnions 12 and the winding roll may be removed.

Other parts of the printing press, such 45 as the vertically reciprocating knife 26, the

gage plate 27 of the board 28 upon which the sheet S falls when cut, and the adjusting device 29, for the board, are more particularly described in co-pending applications for patent, and need not be herein detailed as to their construction. 50

Claims—

1. The combination with a compensating frame comprising side bars vertically movable, of a pair of supporting rolls one of 55 which is positively driven, a winding roll having trunnions and resting upon the supporting rolls, and said side bars detachably suspended from said trunnions, a weighted device connecting the side bars at their lower 60 ends, and means for lifting said device to free the winding roll from the supporting rolls.

2. The combination with a pair of supporting rolls one of which is positively 65 driven, of a vertically movable compensating frame having upper end hooks, a winding roll journaled in the hooks and frictionally engaging the driven roll, a transverse lower shelf forming part of the frame, weights on 70 said shelf, and a release device whereby the completed winding roll may be disengaged from its hooks.

3. The combination with a pair of supporting rolls one of which is positively 75 driven, of two side bars having rack teeth forming a suspended compensating frame, a transverse shelf connecting the lower ends of said side bars and a weight on the shelf, a pivoted lift lever connected to the shelf, an 80 equalizer shaft and rack wheels thereon to engage the rack teeth, hooks at the upper ends of said bars, a core having trunnions journaled in said hooks, whereby a web may be wound on the core by frictional contact 85 with the driven roll.

In testimony whereof we affix our signatures.

ORVILLE VINCENT DUTRO.
ARTHUR S. BURROUGHS.
